ROBERT W. FORD, OF VANCOUVER, BRITISH COLUMBIA, CANADA.

HEATER FOR FLUID MEDIUMS.

1,160,870.

Specification of Letters Patent. Patented Nov. 16, 1915.

Application filed July 21, 1914. Serial No. 852,290.

To all whom it may concern:

Be it known that I, ROBERT W. FORD, a subject of the King of Great Britain, residing at Vancouver, in the Province of British Columbia, Canada, have invented certain new and useful Improvements in Heaters for Fluid Mediums, of which the following is a specification.

This invention relates to a heating device of that class wherein the heat of combustion of the fuel is imparted to a fluid medium by which the heat may be distributed and circulated through a house or building.

The object of the invention is to obtain such delivery of the heated gases from the combustion chamber, and such circulation of the distributing medium past the surfaces of the heated flue that an economical abstraction of the heat may be obtained. This result is attained by conducting the products of combustion, preferably of a liquid or gaseous fuel, along a suitably baffled substantially horizontal flue leading from the chamber in which combustion occurs, to the place of exit to the chimney.

The combustion chamber and the flue are surrounded with a jacket space through which a heat distributing and circulating medium, such as water or air, is induced to move in a direction opposite to that of the products of combustion, with provision enabling the medium as heated to circulate past a surface from which it may absorb further heat. With this arrangement the medium, as it is heated, is not, as frequently occurs in heaters of this class, moved past less heated parts to which it may return a portion of the heat previously derived.

The invention is particularly described in the following specification, reference being made to the drawings by which it is accompanied, in which:

Figure 1 is a vertical longitudinal section through the heater showing the application of the principle to the use of a fluid medium such as water. Fig. 2 is a sectional plan of the same. Fig. 3, a vertical cross section through the combustion chamber on the line A A in Fig. 1, and Fig. 4, a vertical cross section on the line B B on the same figure.

In these drawings 2 represents a shallow cylindrical combustion chamber into which the oil or gaseous fuel with the air for combustion, is delivered through a central aperture 3 in the bottom. From the upper part of this combustion chamber 2 a horizontally

elongated flue 4 is connected, which flue is substantially rectangular in cross section and has a width greater than that of the combustion chamber which it intersects, and a depth which is relatively shallow. From the upper side of this flue a domed crown 5 projects upward over the combustion chamber with which it is concentric, and at the other end the flue delivers through an uptake 6 to the chimney.

The horizontal flue is of sufficient length to enable all available heat to be abstracted from the products of combustion. It is provided with a series of baffles 7 each offering a concave surface toward the combustion chamber 2 and terminating alternately adjacent to the middle line to leave a passage 8 and adjacent to each side of the fuel to leave a passage 9 on each side. The products of combustion will thus be materially checked in their progress to the uptake 6 and will be compelled to travel back and forth across the width of the flue 4.

Where the fuel to be used is such as will form a deposit in the flue 4 the baffles 7 of that flue, which are shown in the drawing as forming a part of and downwardly projecting from the top plate of the flue, will be separate therefrom and will be connected together on a longitudinal frame so as to be removable through the end of the flue adjacent to the uptake which flue end will be produced through that end of the heater for that purpose and be closable with a removable plate.

The shell 20 by which the combustion chamber 2 and its flue 4 are inclosed provides a water space 11 12 surrounding their top, bottom and sides, that space 11 beneath the flue 4 and around the lower part of the combustion chamber being separated from the upper space 12 by a horizontal partition 21 which is outwardly flanged from the casting or plate which forms the crown plate 100 and sides of the flue.

To the lower water space 11 the return water from the heating system is delivered at 10, and communication from this to the upper water space is afforded by apertures 105 13 adjacent to the inlet and through an aperture 14 on each side of the combustion chamber.

Delivery of the heated water from the heater is effected at a dome-like enlargement 110 15 immediately over the combustion chamber 2, to the upper end of which enlarge-

ment the pipe 16 to the circulating system is connected. The depth of the upper water space 12 is uniformly increased from the end adjacent to the inlet 10 to the end on which is the delivery dome 15.

5 Extending around the domed crown of the combustion chamber opposite to that side of it from which the flue 4 extends, is a baffle 17, the sides of which baffle are curved downward toward the flue, and this baffle 17 is hooded partially over the domed crown. A baffle 19 is carried over the length of the flue 4, the sides of which baffle are curved downward toward the flue and this baffle

10 15 is angled slightly upward toward the dome 15 of the outlet. This water space baffle 19 may be continuous throughout its length or may be made in two or more sections each separately sloped upward toward the outlet.

20 The top and sides of the outer shell of the heater are covered with a heat non-conducting casing 22 which is supported on webs 23 upwardly projecting from the shell 20 so as to provide a non-circulating air space 24 between the shell and the external casing. With this design the products of combustion from the chamber 2 are checked in their access to the uptake 6 by the baffles 7 and are diverted back and forth between the middle and the sides across the width of the flue. The heating medium is admitted at 10 to the lower end of the heater farther from the combustion chamber and a portion of it is 25 30 35 directed along the bottom of the flue so that it comes first in contact with the cooler part of it and later with the walls of the combustion chamber before delivery through the apertures 14. A portion of the entering fluid is admitted at the cooler end through the apertures 13 to the space 12 above the flue 4 and becomes gradually heated in its progress toward the combustion chamber end where the greater heat is experienced 40 45 and from which it rises to the outlet 15.

Although particularly described and illustrated as applicable to a water heater the same general principle of design is applicable to where air is the heat distributing medium, with such modification in the construction of the flues and jacket spaces, as may be desirable in providing for the heating and circulation of an elastic fluid medium, such as air.

50 55 Having now particularly described my invention, I hereby declare that what I claim as new and desire to be protected in by Letters Patent, is:

1. A fluid heater, comprising the combination with a cylindrical combustion chamber having a domed crown, of an elongated relatively shallow flue horizontally intersecting the combustion chamber at the base of its crown and extending therefrom to the chimney uptake said flue having curved baffles

the concavity of which is directed toward the combustion chamber and the alternative baffles having apertures in the middle and at the sides of the flue, a heat non-conducting casing inclosing a space around the combustion chamber and flue, a partition horizontally dividing this space in the plane of the bottom of the flue, apertures in this partition adjacent to the uptake and adjacent to the combustion chamber, an inlet delivering the fluid medium to be heated adjacent to the flue uptake, and an outlet for the heated medium from the heater adjacent to the combustion chamber.

2. A fluid heater, comprising the combination with a shallow cylindrical combustion chamber the axis of which is vertically disposed said combustion chamber having a domed crown, and an elongated shallow flue of rectangular cross section intersecting the combustion chamber at the base of its crown plate and extending horizontally to the chimney uptake, a casing inclosing the combustion chamber and its flue, a horizontal partition dividing this space in the approximate plane of the bottom of the flue which partition is provided with apertures adjacent to the uptake and adjacent to the combustion chamber, an inlet admitting a fluid medium into the space beneath the flue adjacent to the uptake, an outlet over the combustion chamber delivering the heated medium, a hooded baffle in the fluid space around the side of the combustion chamber opposite to the flue and baffles over the crown plate of the flue sloping upward toward the fluid outlet.

3. A fluid heater comprising the combination of a combustion chamber, an elongated relatively shallow flue extending with its upper and lower walls in parallel horizontal planes from adjacent to the crown of the combustion chamber, and connected at their end to the chimney uptake, a casing inclosing a space around the combustion chamber and the flue, and an outer shell inclosing said casing, an inlet for delivering fluid medium to be heated into the lower part of said casing adjacent to the uptake, and an outlet for the heated fluid medium over the combustion chamber.

4. A fluid heater comprising the combination of a combustion chamber, an elongated relatively shallow flue extending with its upper and lower walls in parallel horizontal planes from adjacent to the crown of the combustion chamber, and connected at their end to the chimney uptake, a casing inclosing a space around the combustion chamber and the flue, and an outer shell inclosing said casing, an inlet for delivering fluid medium to be heated into the lower part of said casing adjacent to the uptake, an outlet for the heated fluid medium over the combustion chamber, the upper wall of said cas-

ing inclining upwardly from the uptake end toward the combustion chamber end, said combustion chamber including a dome top and a hooded baffle over said dome top within said casing, and a horizontal baffle within said casing over said flue, substantially as described.

In testimony whereof I affix my signature in presence of two witnesses.

ROBERT W. FORD.
